PNEUMATIC DISPATCH SYSTEM

Chester S. Jennings, Syracuse, N. Y., assignor to
 The Lamson Company, Syracuse, N. Y., a corporation of Massachusetts

Application November 11, 1930, Serial No. 494,882

4 Claims. (Cl. 243—19)

This invention relates to pneumatic dispatch systems having stations of the general type comprising a substantially air-tight receptacle which encloses the ends of both the sending and the delivery tubes, at such station, which are so arranged that the carrier transmitting air stream may pass from one tube to the other within the receptacle, which in effect, constitutes a connection between the tubes. The receptacle is usually equipped with one or more doors or other removable closure members for affording access to the sending tube for dispatching carriers as well as to provide for removal of arriving carriers.

To assure proper operation of a system of this kind, the air stream should pass through the receptacle freely, or at least without undergoing any objectionable restriction. For this reason the ends of the tubes within the terminal are kept normally open and it thus might be possible under some conditions for a carrier to pass directly from a delivery tube to a sending tube.

Accordingly it is one of the primary objects of the present invention to improve the construction of terminals of the class referred to by providing improved means, preferably of simple and efficient construction, for preventing a carrier from passing directly from a delivery tube to a dispatch tube. A further object is to provide apparatus for these purposes having an improved construction and relative arrangement of parts.

In accordance with this invention these desirable objectives may be attained by providing movable means, such as a member disposed normally in position to obstruct the article transmitting passage provided by the dispatch tube and yet so proportioned and arranged as not to restrict the air current to any objectionable degree. Preferably this member is adapted either by its own weight or by a resilient or equivalent means such as a spring to remain normally in a position to obstruct the dispatch passage, but is movable in some convenient manner to a position to clear the dispatch passage, as by engagement with a carrier intended for the dispatch tube. While in its normal position, this movable means obstructs the dispatch passage so as to preclude the possibility of the undesirable results previously pointed out herein, it does not in any way interfere with the proper operation of a terminal of the class described.

In the drawings:

Fig. 1 is an end elevation of a pneumatic dispatch terminal equipped with a side door;

Fig. 2 is an enlarged elevational view of the

receiving end of a down-sending tube equipped with an improved guard member;

Fig. 3 is a top plan view of the guard shown in Fig. 2;

Fig. 4 is a side elevation of a terminal of the end door type;

Fig. 5 is a section taken substantially along the line 5—5 of Fig. 6, showing a double side door type of terminal;

Fig. 6 is an end elevation of the terminal shown in Fig. 5;

Fig. 7 is an enlarged elevational view showing the receiving end of a down-sending dispatch tube equipped with another form of guard member; and

Fig. 8 is a top plan view of the guard member shown in Figs. 5 and 7.

The features of the invention are illustrated as embodied in terminals of the type disclosed in the patents to Cowley, Nos. 1,769,676 and 1,769,677, both issued July 1, 1930, to which reference may be had for a more complete explanation of the purposes and mode of operation of apparatus of this character. As shown in Fig. 1 a terminal of this type comprises an air-tight receptacle 10, which may be rectangular in form and equipped with a normally closed side door 11. A down-sending dispatch tube 12 extends through the bottom of this receptacle and is positioned therein to be accessible from the outside when the door 11 is opened. The receiving end of this tube (Fig. 2) is fitted with an internally beveled ring 13 which provides an outwardly flaring mouth or entrance to assist in guiding carriers into the tube. This ring carries circumferentially spaced ears 14 in which a pivot pin 16 is disposed. A guard member 17, equipped with similar ears or lugs 18, 19 which are bored to receive the pin 16, is journaled thereon so that this member may pivot or swing transversely of the tube. The outer or free end portion 21 of the guard member is preferably curved or inclined upwardly or away from the entrance to the tube and the member is so proportioned that the underside of the body thereof normally bears against the ring 13 adjacent the pivotal mounting 16 so as to support this member substantially in the position shown in Fig. 2 in which it will be noted that the member is effective for obstructing the dispatch passage sufficiently to prevent the introduction of carriers therein and yet does not restrict this passage to such an extent as to interfere with the proper circulation of air therethrough.

It will also be noted that the lugs 18 and 19 pro-

ject beyond the pivotal mounting 16 and function as abutment means for engagement with an abutment 22 formed on the ring 13 in a position to limit upward movement of the member 17 to substantially the position shown in the dot and dash lines in Fig. 2. It will be observed that when this member occupies its upper position it leaves the entrance to this tube substantially unobstructed so that carriers may be readily inserted therein. 10 The abutment 22 and the cooperating lugs 18 and 19 are also so arranged as to limit upward movement of the member 17 at a point where it will be in a condition of unstable equilibrium and will therefore tend normally to drop down into the 15 full line position as shown in Fig. 2. It should also be noted that this dispatch tube is arranged in the terminal 10 so that the pivotal mounting 16 is disposed on the side of the tube remote from the door 11. In this way the upwardly turned 20 end portion 21 of the guard member is readily accessible from the doorway for engagement by the nose of a carrier to be introduced into the tube and it will be seen that on engagement by a carrier the guard member will be moved readily to 25 its upper position where it will not interfere with the introduction of such carriers into the tube.

In the modification shown in Fig. 4 the receptacle 26 is equipped with a normally closed end door 27. An article delivery tube 28 enters 30 the bottom of this receptacle adjacent the end wall thereof remote from the door 27 and a curved guard member 29 is arranged for directing carrier issuing from the tube 28 through an arcuate path to a position adjacent the door. This receptacle is also fitted with a down-sending dispatch tube 12 which is equipped with a guard member 17 and is in all respects similar to the dispatch tube described with reference to Figs. 1 and 2. In this modification also the member 40 17 is mounted to pivot at the side of the tube 12 which is the more remote from the door 27. It will be seen that with this arrangement the upper position of the guard member 17 not only is an unstable one as previously described but also if 45 for any reason this member should stick in its upper position the impact of an arriving carrier issuing from the tube 28 would ordinarily be effective either to deflect this carrier from the tube 12 or to cause the guard member 17 to move to 50 its lower position to obstruct the entrance to this tube.

In the modification in Figs. 5 and 6 the terminal comprises an air-tight receptacle 31 equipped with normally closed side doors 32 and 55 33 disposed in substantially opposed relation midway of the side walls of the receptacle. The delivery tube 34 enters the bottom of the receptacle adjacent one of the end walls thereof and an arcuate guard member 36 is arranged for directing articles issuing from the tube 34 to the other end of the chamber provided by this receptacle. A down-sending dispatch tube 37 also enters the 60 receptacle through the floor at a point closely adjacent the delivery tube and preferably in a location readily accessible from either of the side door openings. The dispatch tube 37 (Fig. 7) is equipped with an end ring 38 similar to the ring 13 described with reference to Fig. 2 and provided with a pivotal support 39 on which a guard member 41 is mounted to swing between the lower 65 position shown in full lines in Fig. 7 and the upper position shown in dot and dash lines in this figure.

In this modification the pivotal mounting for the guard member is preferably arranged on the 70 side of the dispatch tube adjacent the delivery

tube and at a point spaced approximately equally from the side doors 32 and 33. The outer or free end portion of this guard member preferably is in the form of laterally diverging tongues 42 and 43 which are inclined or curved upwardly or 80 away from the entrance to the tube 37. It will be seen that the upwardly turned end portion of one of these tongues is disposed in a position to be readily accessible from one doorway while the end portion of the other tongue is likewise accessible from the other doorway. The member 41 is therefore adapted to be moved from its lower or full line position in Fig. 7 to the upper or dot and dash line position by engagement of the nose of a carrier with one of the tongues 42 or 43 to permit 85 introduction of such carrier into this dispatch tube. This guard member is also provided with abutment means 44 for engagement with an abutment 46 on the ring 38 to limit upward movement so that when in its upper position the guard is 90 in a condition of unstable equilibrium and ends therefore to drop to the lower or full line position as shown in Fig. 7 in which its under surface bears on the ring 38 adjacent the pivotal mounting 39. Furthermore it will be seen that the upwardly turned tongues 42 and 43 permit an adequate flow of air into the dispatch tube to assure 95 proper circulation at all times.

While several embodiments of this invention have been shown and described it will be understood that I am not limited thereto and that other embodiments might be made without departing from the spirit and scope of the invention as set forth in the following claims.

I claim:

1. In a pneumatic dispatch terminal comprising a substantially air-tight receptacle, a normally closed door for the receptacle, and delivery and sending tubes terminating within the receptacle, the combination of a member pivotally mounted for movement between a position across the entrance to the sending tube and a position wherein the member leaves the entrance to this tube substantially unobstructed, this member being normally in the former of these positions, and being pivoted adjacent the sending tube at the side adjacent the delivery tube, whereby carriers issuing from the delivery tube may have a tendency on engagement with the member to move the latter to its position across the entrance of the sending tube.

2. In a pneumatic dispatch terminal comprising a substantially air-tight receptacle, a normally closed door for the receptacle, and delivery and sending tubes terminating within the receptacle, the combination of a pivotal support disposed adjacent the entrance to the sending tube, a member mounted on this support for movement between a position to obstruct this tube and a position to clear the tube, abutment means for limiting movement of the member as it arrives at the tube clearing position, these parts being so constructed and arranged that the member is in an unstable condition when in the tube clearing position and tends normally to return to the tube obstructing position.

3. In a pneumatic dispatch terminal comprising a substantially air-tight receptacle, a normally closed door for the receptacle, and delivery and sending tubes terminating within the receptacle, the combination of a member mounted to pivot adjacent the sending tube and at the side thereof remote from the door, the member being movable from a position across the entrance to the sending tube to a position wherein the

member leaves the entrance to the sending tube substantially unobstructed, the member having an outer end portion curved away from the tube for engagement by a carrier thrust through the 5 door, the member being movable on such engagement to the tube unobstructing position to permit the carrier to enter the sending tube.

4. In a pneumatic dispatch terminal comprising a substantially air-tight receptacle, normally 10 closed doors on opposite sides of the receptacle, and delivery and dispatch tubes terminating within in the receptacle, the combination of a member mounted to pivot adjacent the dispatch tube and

at a point spaced approximately equally between the doors, the member being movable between a position across the entrance to the dispatch tube and an upper position wherein the member leaves the entrance to the dispatch tube substantially unobstructed, the outer end portion of the member being in the form of laterally diverging tongues, each tongue curving upwardly and outwardly toward one of the doors for engagement by a carrier thrust therethrough, whereby the member is moved to its upper position to permit the carrier to enter the dispatch tube. 80
